UNITED STATES PATENT OFFICE.

STEPHEN BALLNER, OF CHICAGO, ILLINOIS.

WINDOW.

Application filed September 18, 1926. Serial No. 136,290.

The invention relates to windows and particularly to the kind in which a plurality of sashes are mounted for vertical reciprocation.

5 The cleaning of windows especially in tall buildings has always been a great problem as far as operating expenses are concerned, for the necessity of employing window washers to be on the outside of the building 10 together with the hazard involved, has stimulated endeavors to construct windows enabling the cleaning or washing of both sides of the window panes from the inside of the building.

15 Many ingenious attempts have been made to solve the problem, but they have not found universal recognition because they either involved expensive construction or were not acceptable for practical reasons.

20 It, therefore, constitutes the principal object of the invention to provide a window which permits ready access to both sides of the window panes without requiring a person to be on the outside of the room.

25 Another object aims at providing a window in which the sashes may be completely removed from the frame into the room and conveniently replaced in operative position.

30 A further object aims at providing a window, in which the sashes may be detached from the sash cords or chains and removed in a horizontal direction.

35 It is a still further object of the invention to provide a window where the sashes may be removed frontwise and in like manner installed in the frame for operation.

40 It is also an object of the invention to provide certain features of construction and arrangement which will tend to enhance the usefulness and efficiency of a device of the kind specified.

45 With these and other equally important objects in view which will become apparent from the description of the invention, the latter comprises the means hereinafter described in the specification, particularly pointed out in the claims forming a part thereof, and illustrated in the accompanying drawings, in which:

50 Fig. 1 is a front view of a window constructed in accordance with my invention;

Fig. 2 is a section on the line 2-2 of Fig. 1;

Fig. 3 is a section on the line 3-3 of Fig. 1; 55

Fig. 4 is a fragmentary perspective view of the window frame;

Fig. 5 is a section on the line 5-5 of Fig. 1;

Fig. 6 is a section on the line 6-6 of Fig. 4; 60

Fig. 7 is a section on the line 7-7 of Fig. 6;

Fig. 8 is a fragmentary front view of a window having a modification; 65

Fig. 9 is a fragmentary perspective view of the window frame shown in Fig. 8; and

Figs. 10 and 11 are sections on the lines 10-10 and 11-11, respectively, of Fig. 8.

Referring particularly to Figs. 1-8, the 70 window comprises the pulley stiles 10 and 11 which are arranged between the front casing 12 and the rear casing 13.

To the pulley stiles are secured vertical members known as parting strips 14. The 75 front and rear casings project beyond the inner stile face to provide front stops 15 and rear stops 16. The front sash 17 thus vertically reciprocates between the front stops 15 and the parting strip 14, whereas, 80 the rear sash 18 is fitted for vertical reciprocation between the parting strip 14 and the rear stop 16. As is usual, the window sashes are counterbalanced through sash weights 19 or 20, whose chains or cords 21 85 are trained around pulleys 22 located in slots provided in the upper part of the stiles and thence are detachably secured to the respective sashes so that in any position of the sashes, the same are balanced as will be 90 readily understood by those versed in the art. With the exception of the detachable fastening of the sash cords, the parts thus far described are common to all windows and do not form per se the invention. 95

In order to provide for the convenient complete removal of the sashes the projecting portion of the front casing is cut away from the sill 23 to a point slightly higher than the topmost edge of the front sash 100 when the latter occupies the lowermost position. An angular member 24 is secured to front casing by hinges 25 so that it may be swung into functional position as shown in Fig. 3, in which the member 24 complements 105 the front casing and its leg 24^a abuts the

turn stile or may be swung outwardly as shown in Fig. 4 to enlarge the opening for the front sash 17 to permit the withdrawal of the latter in horizontal direction with the sash being held vertically. This withdrawal of the front sash, however, is only possible after an auxiliary sill 26 hingedly connected to the sill 23 is swung outwardly.

In order to secure the member 24 in functional position, a snap lock (Fig. 3) is provided in a cut out portion thereof comprising a casing 27 in which is arranged a catch member 28 extending with a nose 29 through a slot in the casing, the catch 28 in the form of a bell crank lever pivots on a vertical pin 30 in the casing and terminates with its other end in a thumb plate 31 which is opposite to an opening 32 in the casing 27 to afford access to said thumb plate. A spring 33 is interposed between the thumb plate and the remote casing wall whereby the nose 29 is held inwardly. A cut out 34 in the pulley stile permits entry of the nose 29 and the latter is held by a detention plate 35 secured to the stile to partly cover said cut out 34.

In order to swing the angular member 24 outwardly it will be necessary to depress the thumb plate 31 against the pressure of spring 33 so as to remove the catch nose from the plate 35 whereupon the member may be swung about its hinges to idle or open position.

For the purpose of removing the rear sash the parting strip 14 is cut off to the same extent as the front casing and a strip 36 is secured to the pulley stile by hinges 37 so as to form a complement for the parting strip or to be swung away and received within an extended slot 38 provided in the stile. The strip 36 is held in operative position by an arm 39 which is secured to the angular member 24 and is adapted to bear against the strip 37 when said member occupies the functional position.

In order to conveniently return the strip 36 from idle to functional position, an actuating device is provided on the pulley stile which comprises a lever 40 (Fig. 6) pivotally arranged between upstanding lugs 41 of a plate 42 secured to the stile. The free end of said lever has secured thereto a stem 43 extending in a bore 44 of the stile and terminating in a thumb plate 45. A spring 46 is interposed between the thumb plate 45 and the plate 42 so that the active lever end is held in retracted position. When the strip 36 is in the slot 38 and the thumb plate 45 is pressed the lever 40 forces the strip out of the slot 38 and into functional position as will readily appear from Fig. 6.

From the foregoing the manner of removing the stops will be readily understood.

At first the sill 26 is swung downwardly and both sashes are lifted to topmost position. Thereupon, the thumb plates 31 are

depressed to release the angular members 24 which are swung out. The front sash is then lowered and may then be taken out from the frame front wise, that is, in a horizontal direction without turning the same.

70

Subsequently the strip 36 is swung about its hinges into the slot 38 and after lowering the rear sash, it may be taken out while remaining in vertical position. It is, of course, understood that sash cords are detached from the sashes prior to their removal and the loose ends of the cords are secured in any convenient manner.

75

In Figs. 9 and 11, a slight modification is incorporated to simplify the construction of the invention and to facilitate the removal and replacement of the sashes.

80

In the present case, the angular member 24' and the strip 36' are connected so as to form a rigid structure. As indicated, a plate 50 is secured to the inner face of the leg 24' and extends with tongues 51 and 52 through slots 53 and 54 in the strip 36' and are bent over onto the strip to securely hold the same rigid to the angular member. The snap lock and the retaining plate are substantially the same as described in connection with the first embodiment.

85

90

In removing the sashes, the same are again raised to topmost position and owing to the absence of the auxiliary sill, it is only necessary to depress the thumb plate 31', whereupon the angular member 24' may be swung out. This movement is now participated by the strip 36' so that upon lowering of the sashes, both may be simultaneously withdrawn while in vertical position after the sash cords have been detached and the loose ends temporarily secured for instance by securing the same to studs 55 (Fig. 9) at the lower end of the parting strip.

95

While the drawings disclose preferred embodiments of the invention, numerous changes and alterations may be made without departing from the purview of the invention. I, therefore, do not limit myself to the details of construction or arrangement, but wish to include all changes, re-arrangements, revisions, alterations and modifications constituting departures within the scope of the invention as defined in the appended claims.

100

I claim:

1. A window, including a frame, sashes fitted for vertical reciprocation therein, and a single means pivotally secured to said frame for permitting complete and simultaneous removal of said sash from said frame.

105

2. A window, including a frame, sashes fitted for vertical reciprocation therein, and a single means pivotally secured to said frame for permitting complete and simultaneous removal of said sash from said frame while in vertical position.

110

3. A window, including a frame, sashes fitted for vertical reciprocation therein, and a

115

120

125

130

- single means pivotally secured to said frame and forming a part thereof for permitting complete and simultaneous removal of said sashes from said frame.
5. 4. A window, including a frame having vertical ledges to afford runways, sashes reciprocating in said runways, and a single hinged means for removing a portion of said ledges to clear said sashes for complete and simultaneous removal from said frame.
10. 5. A window, including a frame, formed with vertical runways, sashes reciprocating
- in said runways, and a single means for hingedly removing a portion of said runways to afford clearance for the complete removal of said sashes.
6. A window, including a frame formed with vertical runways, sashes reciprocating in said runways, and a single means affording simultaneous complete removal of said sashes from said frame.

In witness whereof I affix my signature.

STEPHEN BALLNER.
